(57) **CLAIM**

The ornamental design for pad caddy, as shown and described.

DESCRIPTION

FIG. 1 is a top plan view of a pad caddy showing my new design;

FIG. 2 is a left side elevation view thereof;

FIG. 3 is an enlarged rear elevation view thereof;

FIG. 4 is an enlarged front elevation view thereof;

FIG. 5 is a bottom plan view thereof;

FIG. 6 is a top front left isometric view thereof; and,

FIG. 7 is a top rear right isometric view thereof.

The right side elevation view is a mirror image of FIG. 2.
